UNITED STATES PATENT OFFICE.

WILLIAM H. GOLDING, OF CHELSEA, MASSACHUSETTS.

DESIGN FOR A HAND-STAMP.

Specification forming part of Design No. 5,510, dated February 13, 1872.

To all persons to whom these presents may come:

Be it known that I, WILLIAM H. GOLDING, of Chelsea, of the county of Suffolk and State of Massachusetts, have invented or produced a new ornamental Design for a Linen-Marker or Hand-Stamp; and do hereby declare the same to be described as follows and to be represented in the accompanying drawing, of which—

The design has reference to the body of the stamp, or to such and to the head of its plunger.

In such drawing, A denotes the said body, and B the plunger-head, the type-holder being shown at c as carried by the plunger, which, in the construction of the stamp, is furnished with an elevating spring, encompassing the plunger and arranged within the body. The body is formed with a flat bottom, a, with a notch, b, extending up from its middle into the body to receive and guide the part C in its vertical movements. The base b' part of the body is prismatic, with opposite parallel faces c c d d, and is surmounted by a standard vase, f. Each opposite face of the body is arched or rounded, as represented. The plunger terminates in a head or knob, B, formed as represented. The base of the body is formed with opposite parallel faces c c, by which the adjustment of marking implement parallel to any line to which it may be desirable to have the mark parallel can be better effected than would be the case were the body circular in horizontal section at the base.

I claim—

The design for the body of the linen-marker or hand-stamp, as shown and described, or that of the said body and the plunger-head.

WILLIAM H. GOLDING.
